UNITED STATES PATENT OFFICE.

WALTER A. SCHMIDT, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

PROCESS FOR THE PRODUCTION AND RECOVERY OF METALS IN FINELY DIVIDED FORM.

No Drawing.

Application filed March 10, 1921. Serial No. 451,157.

To all whom it may concern:

Be it known that I, WALTER A. SCHMIDT, a citizen of the United States, residing at Los Angeles, in the county of Los Angeles and State of California, have invented a new and useful Process for the Production and Recovery of Metals in Finely Divided Form, of which the following is a specification.

10 This invention relates to the production of metals in finely divided or pulverulent form, as, for example, the production of zinc powder, flour, or dust for use as a precipitant in metallurgy, or for other purposes, the main object of the invention being to provide for the production of zinc dust, or other metallic powder, in an extremely fine state of division.

My process may be carried out as follows:

20 A molten bath, or body of metallic zinc, or other metal, is raised to a temperature sufficiently high to cause volatilization, such operation being conducted in any suitable 25 type of furnace, or retort out of contact with atmospheric air, so as to prevent oxidation of the metal, for example, the operation may be conducted in a furnace of the crucible type, or muffie type, or of the rever-

30 beratory type. The zinc, or other metal, volatilized in this manner as metallic vapor is conducted away from the retort and chilled or cooled in such manner as to produce a fume of 35 solid metal particles, the temperature being lowered sufficiently to cause the separate particles to solidify while still in the form of fume and the resulting fume is collected in the form of an impalpable powder or dust by any desired means, for example, by electrical precipitation.

40 The metallic vapor may pass from the retort in which it is volatilized by reason of the expansive action of its own vapor pressure (the retort containing the melted zinc being externally heated), or, if desired, a more rapid volatilization may be effected by supplying an inert carrier gas, consisting, for example, of products of combustion, or nitrogen, or a reducing gas, such as hydrogen, carbon gas or vapor, such carrier gas or vapor being forced or drawn through the

retort or furnace so as to carry off the volatilized zinc, or other metallic vapor, more rapidly and increase the rate of volatilization. Such carrier gas may also be utilized as a means for supplying part or all of the required heat to the body of zinc, or other metal, to be volatilized. For example, the carrier gas may consist of hot products of combustion taking place in the volatilizing retort, or in a separate combustion chamber, or such hot gases may be pre-heated in any other suitable manner. In case products of combustion are used the same will not be completely inert, but will have some oxidizing effect due to the presence of carbon dioxide and of more or less unbound oxygen, but it has been found in practice that the presence of a small amount of oxidizing gases is not inimical to the process and in some cases, particularly in the production of zinc powder for cyanide precipitation, a slight degree of oxidation is desirable, and my invention includes the use of such an approximately inert gas, as well as a completely inert carrier gas.

45 In order to ensure the production of the zinc, or other metal, in finely divided form it is necessary to provide for chilling of the vapor below the solidifying point without allowing the particles to come in contact with one another to any considerable extent while in liquid condition. For this purpose, it is desirable to cool the body of gases or vapor passing from the furnace in such manner as to cause the formation of a cloud or fume of solid particles suspended in the gas instead of by cooling the walls of the conduit carrying the gas and thereby causing the metal to condense in liquid form on such walls. Such cooling of the gases or vapors carrying the zinc or metal vapor may be effected by injection of cold gas, or other cooling medium, into the body of gas or vapor, such cold gas being, for example, an inert gas, such as nitrogen, carbon dioxide, or other gas free from any tendency to react with the zinc under the temperature existing in the condensing operation. The effect of the supplying or injecting of such relatively cold gas or vapor in the fume carrying body of gas or vapor is to produce a fog or cloud con-

sisting of finely divided solid particles of zinc or metal suspended in the resulting body of gas and vapor, such cloud or fume being then collected by electrical precipitation, or by filter means, such as a bag-house, or otherwise.

The cooling of the gas to form the fume of zinc, or other metal, may be effected by any other suitable means, for example, by suddenly expanding the zinc vapor, or metallic vapor, or the body of gas carrying the same, from a condition of higher to a condition of lower pressure; or a cooling liquid, such as water spray, may be forced into the body of gas or vapor carrying the volatilized zinc. By the process above described, I am enabled to produce zinc dust in the form of an impalpable powder, which by reason of its extremely finely subdivided condition (as compared with that which can be accomplished by granulation or atomization) is especially suitable for precipitation of metals in cyanide leaching processes, and for similar purposes.

The process is also applicable to the production of other metals in finely divided condition. Thus copper or aluminum may be volatilized, for example, in an electric furnace, the vapor condensed to form a fume, and the fume collected to form a finely divided material capable of use as a metallic paint, or for various uses. Copper flour produced in this manner may be used in making dynamo brushes. Aluminum flour so produced may be used in making "thermit". Similarly iron powder may be produced in this manner and used as a precipitant in copper metallurgy, or as a reducing agent for the production of hydrogen from steam, and finely divided nickel produced in the manner above stated may be used as a catalytic agent. In the production of iron or nickel powder, an electric furnace may be used in effecting the volatilization. By volatilizing different metals in this manner and bringing the vapors thereof together and condensing the mixed vapors, a fume may be produced and collected consisting of any desired mixture of metals.

In the manufacture of zinc powder, or other metallic powder, the inert gas used as above described and consisting of products of combustion, carbon monoxide, nitrogen, or any other convenient gas, may be circulated in a closed cycle, that is to say a certain amount thereof may be passed through the furnace and the remainder at a lower temperature introduced into the gas stream to chill and condense the vapors, and then through a precipitator or filter into a gas holder. The gas can be cooled in a cooler placed between the precipitator and the gas holder, or it may be cooled in the gas holder, or between the gas holder and the apparatus in which the metallic vapor is chilled to

form fume, said gas holder being the source from which the cold gas is drawn and blown into the furnace and into the gas or vapor varying the volatilized zinc to chill the same. In case products of combustion are used as approximately inert gas for rapid cooling of the metallic vapor carrying gases in order to produce a fine powder, the gas will not be completely inert, but will have, to some extent, an oxidizing property, and my invention includes the use of such an approximately inert or slightly oxidizing gas as a cooling medium.

As a modification of the operation above described, the zinc, or other metal, may be maintained in molten condition and an inert carrying gas bubbled through the molten bath, so as to carry off zinc or metallic vapor, which is condensed to form a fume, such fume being collected, as above described.

What I claim is:

1. The process which consists in heating material containing metallic zinc in a chamber so as to melt and volatilize the zinc, introducing substantially inert gas into said chamber and thereby ejecting the zinc vapor from said chamber so as to increase the rate of volatilization of the zinc, subjecting the gas passing from said chamber and containing volatilized zinc to condensing and separating operations to recover zinc therefrom in finely divided condition, and returning residual gas to said chamber in cyclic operation.

2. The process as set forth in claim 1, and in which the residual gas is heated before being returned to said chamber.

3. The process which consists in heating material containing metallic zinc so as to melt and volatilize the zinc, withdrawing the vapors of zinc from contact with the said material, introducing into the vapors so withdrawn an approximately inert gas which is cooler than such vapors to cause condensation of metallic zinc in finely divided condition, separating the finely divided zinc so condensed, cooling residual gases and returning the gases so cooled to contact with fresh portions of zinc vapor for condensation thereof in cyclic operation of the process.

4. The process which consists in heating within a chamber, material containing metallic zinc, passing approximately inert gas through said chamber to eject the zinc vapors therefrom, passing cool approximately inert gas into contact with the zinc vapors to condense the same in finely divided condition, separating the finely divided zinc from the said gas, returning a portion of the gas to the chamber for ejection of a further quantity of zinc vapors therefrom, and cooling another portion of the residual gas and returning same to contact with the

zinc vapors for condensation thereof in cyclic operation.

5. The process which consists in heating a metal in a chamber to volatilize such metal, 5 passing gas through said chamber to carry off the volatilized metal, subjecting the gas passing from said chamber and containing volatilized metal to condensing and separating operations to recover metal therefrom in 10 finely divided condition, and returning residual gas to said chamber in cyclic operation.

6. The process as set forth in claim 6, and in which the residual gas is heated before 15 being returned to said chamber.

7. The process which consists in heating a metal to melt and volatilize the same, withdrawing the volatilized metal from contact with the melted metal, introducing into 20 the volatilized metal so withdrawn gas which is cooler than such volatilized metal, so as to cause condensation of metal in finely divided condition, separating the metal so

condensed, cooling residual gas and returning the gas so cooled to contact with fresh 25 portions of volatilized metal for condensation thereof, in cyclic operation of the process.

8. The process which consists in heating a metal in a chamber to volatilize such metal, 30 passing gas through said chamber to carry off volatilized metal, introducing into the gas leaving said chamber and containing volatilized metal, gas which is cooler than such volatilized metal so as to cause condensation thereof in finely divided condition, separating such condensed metal from the gas, returning a portion of the residual gas to said chamber, and cooling another portion of said gas and returning same to 40 the gas leaving said chamber, in cyclic operation of the process.

In testimony whereof I have hereunto subscribed my name this 24th day of February, 1921.

WALTER A. SCHMIDT.
